(57) **CLAIM**

The ornamental design for a computer screen with animated graphical user interface, as shown and described.

DESCRIPTION

FIG. 1 is a front view of a first embodiment of a computer screen with animated graphical user interface showing a first image in the sequence according to our design;

FIG. 2 is a second image thereof;

FIG. 3 is a third image thereof;

FIG. 4 is a fourth image thereof;

FIG. 5 is a front view of a second embodiment of a computer screen with animated graphical user interface showing a first image in the sequence according to our design;

FIG. 6 a second image thereof;

FIG. 7 a third image thereof;

FIG. 8 a fourth image thereof; and,

FIG. 9 is a fifth image thereof.

In the Figures, (i) the broken line showing the computer screen forms no part of the claimed design; and (ii) the broken lines showing the graphical elements and text form no part of the claimed design.

In the first embodiment, the appearance of the animated graphical user interface sequentially transitions between the images shown in FIGS. 1 through 4. In the second embodiment, the appearance of the animated graphical user interface sequentially transitions between the images shown in FIGS. 5 through 9.
